UNITED STATES PATENT OFFICE.

AURELIUS V. PITTS AND MARCELLUS H. PITTS, OF MARSEILLES, ILLINOIS,
ASSIGNORS TO THE PITTS MANUFACTURING COMPANY, OF SAME PLACE.

CORN-SHELLER.

SPECIFICATION forming part of Letters Patent No. 361,644, dated April 19, 1887.

Application filed October 24, 1885. Renewed October 2, 1886. Serial No. 215,196. (No model.)

To all whom it may concern:

Be it known that we, AURELIUS V. PITTS and MARCELLUS H. PITTS, citizens of the United States of America, residing at Mar- 5 sellies, in the county of La Salle and State of Illinois, have invented certain new and useful Improvements in Corn-Shellers, of which the following is a specification, reference being had therein to the accompanying drawings.

10 Figure 1 is a side elevation of the sheller with a swinging cob-carrier at one end, a feed-elevator at the opposite end, and a side elevator for elevating shelled corn, all mounted on trucks for transportation. Fig. 2 is a longitudinal vertical section of the sheller, the cob-carrier being detached, and also showing a side view of the yielding breast and endless traveling bed. Fig. 3 is a plan view on the engaging-surface of a portion of the yielding 15 breast. Fig. 4 is a side view of a section of the yielding breast and a cross section of the side bars for holding its sections in place and of the longitudinal bars above for holding the coil-springs between them and the sections of the breast. Fig. 5 is a vertical cross-sectional 20 view of the sheller, taken on line 2 2 of Fig. 1, looking in the direction of the arrow. Fig. 6 is a plan view of a portion of the sieve for separating the shelled corn from the cobs. Fig. 7 is a plan view of a section of the endless traveling bed. Fig. 8 is a rear view of the lower 25 end of the swinging cob-carrier, showing the parts for supporting it. Fig. 9 is a front view of the mechanism for driving the endless conveyer of the swinging cob-carrier. Fig. 10 is a side view of the lower end of the swinging cob-carrier, showing the manner of the attachment of the belt for driving its conveyer; and Fig. 11 is a plan view of the upper end of the 30 toothed endless traveling bed, showing the stationary teeth at its sides, attached to the machine-frame, and the two spring-arms for conducting the ear corn to the center of the traveling bed.

35 This invention relates to certain improvements in corn-shellers, which improvements are fully set forth and explained in the following specification and claims.

Referring to the drawings, A represents the 40 sides of the machine, inclosed within the vertical posts P, P, and P' and resting on the sills

S and held together by means of proper cross-beams, and provided with a pair of sills, B, secured to the lower part, at the sides of the machine, for supporting it on proper trucks and 45 for supporting at the front end an endless carrier, for feeding the machine, and an endless swinging cob-carrier at the rear end, as shown in Fig. 1.

H is an endless traveling bed, located longitudinally within the machine, between its sides A, and mounted on the sprocket-wheels W' and sheaves h, as shown in Fig. 2, the sheave-wheels h being on shaft S' and the sprocket-wheels W' on shaft R, the latter being the 50 drive-shaft. The endless traveling bed H is formed, as shown in detail in Fig. 7, from a pair of sprocket-chains, m' m', the alternate links of which are provided with inwardly-projecting eye-lugs for the attachment of the 55 toothed sections H', as shown in said figure.

Each sprocket-chain m' m' travels on a sprocket-wheel W' and on a sheave h, such as is shown in Fig. 2. The toothed sections H' of the traveling bed, when attached to said 60 sprocket-chains, are arranged to be contiguous to each other, so that grain will not fall between them in the shelling operation.

The shaft S', upon which the sheaves h are mounted, is supported in sliding boxes arranged in rectangular frames J, (see Figs. 1 and 2,) mounted on the front ends of the side beams, P'', of the sheller. Screws i, arranged 65 in vertical posts P, engage said sliding boxes, for the purpose of giving tension to said endless traveling bed.

Guiding-plates G² are arranged in the sides of the sheller in such manner as to project under the sprocket-chains m' m' of the endless traveling bed to properly hold that portion of 70 the traveling bed next the breast above to its work.

The yielding breast N, which is arranged immediately above the upper surface of the toothed endless traveling bed, is constructed 75 as shown in Figs. 3 and 4, and consists of a series of contiguous yielding sections, each composed of a block, n, having a metal plate, Q, fixed on its upper surface and a plate, N', on its lower surface, some of which plates N' 80 may be toothed or ribbed and some plain. The blocks n are made shorter than said plates,

so as to leave recesses for the reception of the bars r , as shown in Fig. 4, said recesses being wider than said bars, to permit vertical movement of said sections. At each end of the said 5 yielding sections is arranged a cross-bar, r^3 , connecting the said bars r , and upon which are secured the longitudinal bars g , as shown in Fig. 2. The bars g are each recessed immediately over each section of the breast for the 10 reception of coil-springs b , which are arranged in pairs between said bars and each section of the breast, as shown in Fig. 4, so that each section may be yieldingly and independently held to its work. The ends of the side bars, 15 r^3 , terminate in eyes, and are pivotally connected to a pair of arms, T T , on each side of the machine, the upper ends of which arms incline toward each other and are slotted for the reception of bolts, by means of which they 20 are secured to the inner sides of the machine, as shown in Figs. 2 and 5, and are for the purpose of permitting slight vertical movement of the breast and preventing its longitudinal movement. The breast is suspended by means 25 of the screw-threaded rods d^4 and y' , as shown in Figs. 2 and 5.

The rods d^4 pass up through perforations in plates d' , secured to the cross-bars z and z' of the machine. Cylindrical rubber cushions d^2 30 are sleeved on said rods d^4 , and held up against said plates d' by means of nuts turned on said rods; and thumb-nuts turned on said rods and down on said plates securely hold said rods in proper position, and, together with the nuts 35 below said cushions, furnish means for the vertical adjustment of the breast. The rods y' pass up through boxes attached to the side of the cross-bar z' of the sheller, and are similarly provided with nuts and cushions as rods 40 d^4 , and are for the same purpose. The inner sides of the sheller are provided with a series of teeth, i' , arranged between the traveling bed H and the breast N , (shown in Fig. 2,) for the purpose of assisting in the shelling operation 45 at the sides of the machine.

The mechanism for feeding ear corn to the sheller is shown in Figs. 1 and 2, and consists in an inclined trough, M , hopper M' , and shafts R^2 and m , upon which are secured pulleys, on 50 which an endless carrier, d , is mounted between the sides of said trough, said feed mechanism being attached to the machine, so as to deliver ear corn to the endless traveling bed, as shown by the arrows in Fig. 2. A pair of cross-guide boards, I and I' , located as shown in Fig. 2, serve to properly guide the ear corn to the endless traveling bed, and a pair of spring-arms—such as is shown at e' in Figs. 2 and 11—are secured to the inner sides of the 55 sheller immediately over the inner end of the traveling bed, and their inner extending ends converge to conduct the corn to the center of the sheller, the inner side of one of said spring-arms being shown in Fig. 2 and the two being 60 shown in Fig. 11.

A curved shield, B' , is arranged to fill the space between the sides of the sheller and im-

mediately in the rear of the endless traveling bed, as shown in Fig. 2, and is for the purpose of preventing the shelled grain from being 70 scattered out of the sheller. A depending apron, A^2 , suspended from the lower side of said shield, assists in preventing the scattering of the grain.

A vibrating sieve-shoe, D , is suspended by 75 means of arms G and G' immediately under the rear end of the traveling bed, and is provided with a sieve, D'' , upon which the cobs and shelled grain fall. The sieve is made from a plate of sheet metal, having its meshes formed 80 by cutting portions of said plate in a circular form, and so as to leave the cut-out portions integral at one side with said plate, said cut portions being alternately bent to project upward and forward and downward and backward, 85 as shown in Figs. 2, 5, and 6.

The sieve-shoe D is caused to vibrate by means of its connection with crank-shaft R^2 through the medium of pitman D' , which is pivotally connected to said shoe, as shown in 90 Fig. 2. The movement of said shoe in its vibration is forward and upward and backward and downward.

The upward-extending projections of the sieve serve to carry the cobs out of the sheller, 95 and the downwardly-extending portions of the sieve serve to conduct the blast of wind from the fan up through the perforations in the sieve while the grain is falling through them and through the grain thereon to more thoroughly clean it of chaff. The grain drops from the sieve on an inclined floor, which conducts it to an inclined spout, G' , which in turn conducts it to the elevator F , at the side of the machine. 105

The fan that creates the wind blast is shown at E^2 , and is placed on shaft R' and rotates in the case K , constructed to convey the wind blast in the proper direction, as shown in Fig. 2. As the grain is elevated in the elevator F , 110 it is discharged at the spout F' , from whence it may be conveyed by a secondary spout in any direction.

The cob-carrier E is shown in Figs. 1, 8, and 10, and consists of an inclined trough pivotally 115 mounted on the cross-bar t , secured to the rear ends of the sills B through the medium of standard t , and is arranged to have its outer upper end turned in any direction within certain limits to discharge the cobs where desired, and is supported at its outer end by suitable legs, as shown in Fig. 1. Each end of the carrier E is provided with a cross-shaft properly boxed thereto and having suitable pulleys upon which an endless belt is mounted. 120 The shaft at the lower end of said carrier is provided with a sheave-pulley, O^5 , to which power is applied to drive said endless carrier through the medium of belt O' , as shown in Fig. 10, from the mechanism shown more particularly in Fig. 9, which consists of a pair of short horizontal shafts and a short perpendicular shaft connected through the medium of two pairs of miter-gears, V and V' , the lower 125 130

horizontal shaft being properly boxed to a cross-bar on the rear part of the sheller, and having a sheave-pulley, e , on its outer end, to which power is applied to drive it.

5 The short vertical shaft rests in a step-box on said cross-bar, and is properly supported by a stationary box immediately above its lower miter-gear. Boxed to said vertical shaft above its stationary bearing is a swinging 10 frame, O^3 , which has the upper horizontal shaft boxed in its upper part. The outer end of said frame rests upon semicircular frame O^4 , and has a hooked bolt, O^2 , arranged therein to clasp said frame O^4 and hold said frame O^3 15 in any position. The said upper horizontal shaft is provided with a sheave-pulley on its outer end, as shown in Figs. 1 and 9, to drive belt O' to operate the cob-elevator. The vertical shaft to which frame O^3 is boxed stands 20 directly over the pivotal support of the cob-carrier. As the cob-carrier is turned in any desired direction, the swinging frame O^3 may be turned correspondingly, so that belt O' may be properly operated to drive the cob-carrier. 25 elevator, while the lower horizontal shaft remains in a stationary position. By this construction the cob-carrier may be turned to deliver cobs in any desired direction, and the mechanism that drives it turned in a corresponding direction to operate it at the will of 30 the operator.

The drive-shaft R is provided with the large drive-pulley Q' , and a smaller belt-pulley, a' , at one end, and a balance-wheel, W , and a 35 pair of belt-pulleys, a and a' , at its opposite end. A belt, C^5 , mounted on pulley a' and pulley a^6 of elevator F , serves to operate said elevator. A belt, c' , mounted on pulley a of shaft R and pulley a^3 of shaft R^3 , serves to 40 drive said shaft R^3 , which is cranked to drive the sieve-shoe. A pulley corresponding with pulley a^3 is arranged at the side of the latter on shaft R^3 , and has mounted thereon belt C^4 , which drives pulley e to operate the cob-carrier. 45 The belt C , mounted on pulley a' and pulley a^2 of shaft R^2 , serves to operate the feed-elevator; and a belt, C^2 , mounted on pulley a^5 of shaft S' , which supports the front end of the endless traveling bed, and a pulley, a^4 , on 50 shaft R' of the fan serve to operate said fan by means of the motion given pulley a^5 through the medium of traveling bed H from the drive-shaft R .

The belt O' , which transmits power from pulley O to pulley O^5 to operate the endless conveyor of the cob-carrier, is shown as passing over a pair of idler-pulleys, O^6 , which are attached to one side of the cob-carrier trough for the purpose of holding said belt away from the sheller, so that it will not engage and be dislocated by projecting parts when the cob-carrier is being swung from side to side. The cob-carrier may, however, have a sheave-pulley secured on its upper cross-shaft and the belt O' may be arranged thereon, if desired, running straight out from pulley O , which

would operate the endless conveyer of the cob-carrier in like manner, as shown.

To operate the machine, the endless feed-elevator M delivers the ear corn to the upper end of the toothed endless bed H , by means of which it is carried between it and the yielding breast above, which is set a little farther distant from the endless bed at its upper front end than at its lower end, so as to make room 75 for large quantities of ear corn to enter between them, the ears being larger with the corn on than the cobs are with the corn off.

It is intended that the corn will be shelled by rolling the ears between said parts, which 80 reduces friction to its lowest limit in corn-shelling. Should an ear chance to enter the machine endwise, the plain sections of the yielding breast permit it to be turned so as to roll, as stated, the sections thereof having but 85 a single rib to assist it to turn. When so large a quantity of corn has entered the machine as to elevate the sections of the breast beyond the limit of the recesses in the ends of said sections, then the rubber cushions d^2 y^2 90 operate to make the breast still more yielding, to prevent injury to the parts. When it is desired to operate the sheller by means of a tumbling-rod, a coupling-link for that purpose may be attached to the outer end of shaft R . 95

Having thus described our invention, what we claim as new, and desire to secure by Letters Patent, is as follows, to wit:

1. In the sheller shown and described, the yielding breast N , consisting of the several independently-yielding sections, arranged and supported as set forth, and having some of said sections provided with teeth or ribs on their engaging-surfaces and some left plain on their engaging-surfaces, for the purpose specified. 100

2. In the corn-sheller shown and described, the yielding breast N , having the side bars, r^r , longitudinal bars g , and coil-springs b , in combination with the arms $T T$, having their lower ends pivoted, respectively, to the outer ends of the said side bars and their upper ends slotted and inclined toward each other and secured to the inner walls of the sheller-frame, bolts passing through said slots, the screw-threaded rods d^4 and y^4 , having the rubber cushions d^2 and y^2 , 110 and nuts at each end thereof for vertical adjustment of said cushions and breast, and the endless traveling bed H , substantially as and for the purpose set forth. 115

3. In the corn-sheller shown and described, the yielding breast N , having the side bars, r^r , longitudinal bars g , and coil-springs b , in combination with the arms $T T$, having their lower ends pivoted, respectively, to the outer ends of the said side bars and having their upper ends 125 slotted and inclined toward each other and secured to the inner sides of the sheller-frame, and bolts passing through said slots, substantially as and for the purpose set forth.

4. In the sheller shown and described, and in combination with the toothed endless traveling bed H and yielding breast N , the side

converging arms, e' , for guiding the ear corn to the central part of said traveling bed, the cross guide-boards I and I', for properly guiding ear corn to said traveling bed, and a suitable feeding mechanism for delivering ear corn to the machine, as and for the purpose set forth.

5. In the corn-sheller shown and described, and in combination with the traveling bed H and yielding breast N, the teeth i' , arranged along the inner sides of the sheller on a line between said endless traveling bed and yielding breast, as and for the purpose set forth.

6. In the corn-sheller shown and described, and in combination with the endless traveling bed H, the yielding sectional breast N, having a portion of its sections toothed or ribbed and a portion of its sections without teeth or ribs,

and the means for yieldingly supporting and preventing longitudinal movement of said breast, substantially as set forth.

7. In the corn-sheller shown and described, the combination of the swinging endless cob-carrier E, pivotally supported on the main frame of the machine, the sheaves or pulleys e O O⁵ O⁶ and their shafts, the bevel-gears V V', stationary frame O⁴, the swinging frame O³, the belt O', and the bolt and thumb-nut O², as and for the purpose set forth.
